STRIPPING MECHANISM

Original Filed Feb. 9, 1938

UNITED STATES PATENT OFFICE

2,225,457

STRIPPING MECHANISM

Adolph Langsner, Chicago, Ill., assignor to Eugene Dietzgen Co., Chicago, Ill., a corporation of Delaware

Original application February 9, 1938, Serial No. 189,666. Divided and this application October 29, 1938, Serial No. 237,615

3 Claims. (Cl. 91—51)

My invention relates in general to sheet treating apparatus and has more particular reference to a simplified machine including a roller for transporting and treating sheet material with a desired treating medium, and including means for stripping the treated material from the roller.

An important object of the invention is to provide improved means for stripping sheet material from a treating roller after the material has been caused to pass in substantially uniform contact throughout its area with a treating roller substantially uniformly coated with the treating medium.

Another important object is to provide mechanism of the character mentioned, including a sheet-treating roller, and at least one sheet-holding roller shiftably mounted and adapted normally to frictionally engage the treating roller to insure engagement of the material being treated with the treating roller, and including stripping means for releasing the material from the treating roller; a further object being to arrange the stripping means for shifting movement with the holding roller to release the treating roller.

Another important object resides in providing improved stripping means in an apparatus of the character mentioned for insuring release of the material being treated from the treating roller at the conclusion of the treatment.

Another important object resides in mounting the sheet-guiding and holding means and also the sheet-stripping means on a frame tiltable with respect to the treating roller, whereby the sheet-guiding means, as well as the stripping means, may be shifted as a unit from operating position with respect to the treating roller to release the material being treated and to simultaneously disconnect the treating roller from the source of driving power; a further object being to support the guiding and holding means and also the stripping means with a slight, though appreciable, amount of play in the tilting frame to permit the same to rest by gravity upon and align themselves with respect to the treating roller when the tilting frame is moved to the operating position, whereby more particularly the guiding means is self-adjusting to accommodate sheet material of any thickness in the apparatus and to assure proper stripping relationship of the stripping means upon the treating roller throughout its entire width.

Numerous other objects, advantages and inherent functions of the invention will become apparent as the same is more fully understood from the

following description, which, taken in connection with the accompanying drawing, discloses a preferred embodiment of the invention.

Referring to the drawing,

Figure 1 is a perspective view of sheet-treating apparatus embodying my present invention;

Figure 2 is a similar perspective view showing the tilting frame and the guiding and stripping means carried thereby, the frame being shown in released position; and

Figures 3 and 4 are sectional views taken substantially along the lines 3—3 in Figure 1 and 4—4 in Figure 2.

To illustrate the invention I have shown on the drawing a sheet-treating apparatus 11 comprising a main frame 13 and a tilting frame 15 carrying rollers for receiving and transporting sheet material through the apparatus, while at the same time applying to the material as it is carried along a suitable treating medium supplied from a source 17.

The main frame 13 preferably comprises a pair of spaced-apart end pieces 19 having feet 21, the end pieces being supported and rigidly braced in spaced-apart position by means of connecting rods 23 fastened therebetween in any suitable fashion, preferably by bolting the rods onto the end pieces 19.

The end pieces may be arranged to support a roll of sheet material to be treated. This, of course, may be accomplished in any suitable or convenient fashion, although I prefer to form the end pieces as shown, with an inclined notch 25 in the forward edges of the end pieces. These notches are adapted removably to receive an axle 27 on which may be rolled and conveniently stored a quantity of sheet material 29.

The end pieces 19 are formed with journals for receiving a driven roller 31 which extends between the substantially mid point of the upper edges of the end pieces. This roller 31 has an axle projecting outwardly of one of the end pieces 19, and means, such as the reduction gearing 33, is preferably provided for connecting the projecting shaft of the roller 31 with a suitable source of driving power which may comprise an electric motor 35 suitably mounted as on a bracket 37 secured to the end piece through which the projecting shaft of the roller 31 extends.

The end pieces also are formed with bearings 39 for a following roller 39 positioned immediately above and parallel with respect to the driven roller 31, the bearings of the roller 39 being formed with sufficient play to permit the roller 39 to rest by gravity upon the roller 31, the roll-

ers being adapted to separate to permit sheet material of any width to pass therebetween.

An inclined, preferably sheet metal plate 41 forming a sheet-feeding surface is secured between the end pieces 19 along the upper edges thereof in front of the rollers 31 and 39, so that material to be treated may be pushed across the feeding surface of the plate 41 and guided between the rollers 31 and 39. The material thus fed may be a continuous strip drawn from the roll of material 28 or may be individual sheets, manually or otherwise delivered across the table 41 to the feeding rollers 31 and 39.

Rearwardly of these feeding rollers the end pieces 19 are formed with notches 43 in the upper edges of the pieces 19. The notches 43 are in alignment transversely of the frame 15 and serve to receive the axles 45 projecting at the ends of a treating roller 47 which is thus supported for rotation in the main frame preferably in a fashion permitting ready removal of the roller 47 from mounting position by merely lifting it upwardly to raise the axles 45 from the slots 43.

Beneath the roller 47 the frame carries means forming a trough 49 adapted to receive a preferably liquid sheet-treating medium 51 which is maintained at a desired level in the trough 49. Any suitable arrangement may be employed to apply the treating medium as a substantially uniform film upon the treating roller 47, and in the illustrated embodiment this is accomplished by positioning the trough 49 so that the lower portions of the roller 47 are immersed in the bath of liquid 51. To this end, the pieces 19 are formed 35 on their inwardly facing surfaces with support means 53 adapted to receive the opposite ends of the trough 49 and support the same in the desired position with respect to the roller 47.

I also provide means for continuously delivering the liquid-treating medium 51 to the trough in order to maintain a desired liquid level therein, and, as shown, the trough is provided with a charging conduit 55 opening, preferably, into the bottom of the trough 49 and extending thence through a suitable opening formed in one of the end pieces 19. Outwardly of said end piece the conduit 51 is connected in any suitable fashion with a charging funnel 57 which is supported in a bracket 59 on the end piece 19.

50 The funnel 57 internally is formed with projections 61 forming one or more upwardly facing shoulders 63, the funnel being supported in the bracket 59 at an elevation such that the shoulders 63 are in approximate alignment with the liquid level to be maintained in the trough 49.

The end piece 19 also carries a bracket 65 forming a clip for receiving and supporting the supply source 17 on the main frame of the device. The supply source, of course, may have any suitable form, but I prefer to employ a common bottle, the support clip 65 being adapted to firmly receive the lower portions of the bottle in order to support the same with its neck extending in the funnel 57 in position resting upon the shoulder 63. A container, such as a bottle supported in this fashion, will maintain the desired level of liquid in the trough 49 as long as the bottle itself contains any liquid. When the bottle becomes empty, it may easily be removed from the clip 65 and replaced with a full bottle without interrupting the operation of the apparatus.

Material delivered between the rollers 31 and 39 will be carried thence and delivered into contact with the roller 47. Since there is no direct positive connection between the roller 47 and the driv-

ing means 38, the roller 47 may be quickly and easily removed from operating position for the purpose of cleaning the same or for repair or replacement. When the apparatus is in operation, however, I desire to connect the roller 47 so that it may be driven at the same peripheral speed at which the rollers 31 and 39 are rotated by the motor 35. To this end and, further, to insure that the sheet material being treated is maintained in substantially uniform contact with the treating roller 47 during its passage thereover, I form the tilting frame 15 with a sheet-guiding roller 67 which, when the frame is in the elevated position shown in Figure 2, is disconnected from the driven roller 31 as well as the treating roller 47, the frame being arranged, when in elevated position, to support the roller 67 in a position permitting the roller 47 to be removed from mounted position for the purposes heretofore mentioned. The tilting frame 15, however, may be lowered to 20 a position in which the roller 67 rests firmly upon the surfaces of the rollers 31 and 47, and thereby provides a driving connection between the driven roller 31 and the treating roller 47. The roller 67 also functions when in operating 25 position to direct the material being treated from the roller 31 and onto the roller 47.

I also prefer to provide an additional roller 69 in the tilting frame 15, said roller 69 being parallel and adjacent with respect to the roller 67 and 30 in position to rest upon the surface of the roller 49 when the frame is in operating position. The roller 69 serves to maintain the material being treated in contact with the treating roller 47 throughout a substantial area of said treating 35 roller.

Since the treating medium 51 is preferably and usually a liquid, the sheet material may have a tendency to adhere upon the surface of the treating roller. To prevent this tendency from carrying the sheet material around the roller and through the bath 49, I provide stripping means 71.

The stripping means comprises a plurality of spaced lifting fingers adapted to bear upon the 45 surface of the roller 47 at intervals throughout the width of the treating roller, in order to insure separation of the sheet material being treated at the termination of the period of treating contact on the roller. Since I wish to provide for the 50 ready removal and replacement of the roller 47 for the reasons heretofore stated, I arrange the spaced fingers comprising the lifting means in the tilting frame 15 so that these fingers may be entirely released and removed from the roller 47 55 when the tilting frame is elevated.

To this end the tilting frame 15 comprises a shaft 73 which is journaled at its opposite ends in bearings formed in the upper, rearward corner portions of the end elements 19, the opposed 60 ends of the shaft 73 preferably projecting outwardly of the end pieces 19 and receiving each an end member 75 of the frame 15. These end members 75 provide bearings for the rollers 67 and 69, and also are interconnected by means of a 65 bar 77 secured in place on the members 75 in any suitable fashion, as by cotter-pins 79.

The fingers forming the stripping means 71 preferably comprise sheet metal stampings 81 having pointed tips 83 at one end thereof for the 70 purpose of riding upon the surface of the roller 47 to separate the sheet material from the roller when it reaches said pointed ends of the fingers 81. The ends of the fingers 81 opposite from the sheet lifting portions are notched, as at 85, to 75

receive the shaft 13 of the tilting frame, said shaft being grooved at intervals, as at 87, to receive the notched ends 85 of the sheet-lifting fingers and to prevent displacement of said 5 notched ends axially on the shaft 13.

Between their opposed ends the fingers 81 are provided with openings 89, through which the shaft extends, in order to maintain the fingers 81 in proper alignment in the frame and to raise 10 the same from the roller 47 when the frame is moved to the elevated or inactive position. The fingers 81, however, are relatively loosely mounted on the rod 17 in order that when the frame is in depressed or operating position the pointed ends 15 of the fingers may rest upon the surface of the treating roller 47 in order that the fingers may each be self-aligning and press upon the roller under the influence of its own weight. In order to facilitate manipulation of the tilting frame 15, 20 the end pieces 75 thereof may be formed with handles 91. It will be noted that the fingers 81 may be removed from mounted position for repair or replacement without dismounting the frame 15 or otherwise disturbing it. This may be 25 accomplished merely by removing the pins 79 and sliding the shaft 11 first one way and then the other to disconnect its ends from the frame members 75 whereupon all of the fingers 81 may be lifted, on the shaft 11, bodily from the notches 30 of the shaft 13 and thus removed from the tilting frame.

The sheet-treating apparatus of my present invention is relatively simple and inexpensive to make. It is, however, positive and automatic in 35 action and will successfully accommodate sheets of any thickness, provided the material is sufficiently flexible to travel the somewhat serpentine path between the rollers 31, 47, 67 and 69. The apparatus also is simple from an operating stand- 40 point, and affords, among others, the advantage of a readily removable treating roller 47 which does not require disassembly of driving connections in order to permit removal of the roller for inspection, cleaning, repair or replacement. At 45 the same time, the apparatus provides guiding rollers for insuring that the material being treated travels the desired pathway across the treating roller, and also simple and inexpensive, yet positively acting, stripping means for insuring 50 the release of the material from the treating roller after the completion of the treating process. These stripping fingers, however, do not in any way interfere with the ready removability of the treating roller for the purpose heretofore 55 mentioned.

The driving and guiding roller is self-aligning and not only insures the delivery of the sheet material to the treating roller, but also insures that the treating roller is driven at the same per- 60

ipheral speed as the sheet-feeding roller 31. The apparatus also provides for a continuous and ample supply of the liquid treating medium 65 by virtue of the improved means for maintaining a desired liquid level in the trough 49 from a remote and readily renewable source of supply 17.

It is thought that the invention and numerous 70 of its attendant advantages will be understood from the foregoing description, and it is obvious that numerous changes may be made in the form, construction, and arrangement of the several parts of the illustrated apparatus without departing from the spirit or scope of my invention or sacrificing any of its attendant advantages, the

forms herein described being merely for the purpose of illustrating the invention; and, except in incidental combination with the stripping means, I do not herein claim the treating roller, the motor driven feeding roller, nor the shiftable 5 transferring and guiding rollers, nor the arrangement of the transferring roller as a driving connection between the motor driven and the treating rollers, since the same forms the subject-matter of invention claimed in my copending application, Serial No. 189,666, filed February 9, 1938, for Sheet treating apparatus which matured as United States Letters Patent No. 2,142,318, issued January 3, 1939, of which the present application 10 comprises a division. 15

The invention is hereby claimed as follows:

1. Stripping means for use with a sheet treating roller comprising a shaft having means thereon forming spaced apart annular grooves in the shaft, said shaft being adapted for mounting 20 adjacent the roller, a plurality of stripping fingers having notched ends receiving the shaft at said grooves, said notched portions of the fingers being received in said grooves whereby to maintain the fingers tiltably in spaced apart relation on 25 said shaft, said fingers being freely removable from mounted position on the shaft by withdrawing the same from the shaft in a direction away from the open ends of said notches, said fingers having sheet releasing portions adapted normally 30 to bear upon the surface of the roller, and a stem common to all of said fingers and extending loosely in an opening in each whereby said stripping fingers are relatively free for independent 35 tilting movement on said shaft so that each may be normally urged by the gravity action of its own weight into contact with said roller, said stem serving as a holder whereby all of the fingers may be simultaneously disconnected from the shaft by withdrawing them from engagement in the 40 notched portions thereof.

2. Stripping means for use with a sheet treating roller comprising a shaft having means thereon forming spaced apart annular grooves in the shaft, said shaft being adapted for mounting 45 adjacent the roller, a frame mounted for tilting movement about the axis of said shaft, a plurality of stripping fingers having notched ends receiving the shaft at said grooves, said notched portions of the fingers being received in said grooves 50 whereby to maintain the fingers tiltably in spaced apart relation on said shaft, said fingers having sheet releasing portions adapted normally to bear upon the surface of the roller, and a stem mounted in said frame and extending loosely in 55 an opening in each of said fingers whereby when the frame is in stripping position said stripping fingers are free for independent movement on the shaft so that each may be normally urged by the gravity action of its own weight into contact with 60 said roller, said stem serving as a holder to retain said fingers with their notched ends in engagement with the grooved portions of said shaft.

3. Stripping means as set forth in claim 2 wherein said frame is provided with roller means 65 in position to be engaged by a portion of said treating roller when the frame is in stripping position in order to support the same in a predetermined relationship with respect to the treating roller to permit the sheet releasing portions of 70 said fingers to ride freely on the surface of the treating roller without restraint by said stem.

ADOLPH LANGSNER.
